United States Patent Office.

L. W. SPENCER, OF NEW YORK, N. Y.

Letters Patent No. 75,805, dated March 24, 1868.

IMPROVEMENT IN MACHINE FOR CUTTING TOBACCO.

The Schedule referred to in these Letters Patent and making part of the same.

TO ALL WHOM IT MAY CONCERN:

Be it known that I, L. W. SPENCER, of the city and county of New York, in the State of New York, have invented certain new and useful Improvements in Machinery for Producing Fine-Cut Tobacco; and I do hereby declare that the following is a full and exact description thereof.

My invention relates to the means for compressing and feeding forward the properly sweetened and otherwise prepared leaves of tobacco, to means for maintaining a very sharp condition of the cutters, and to means for avoiding the accumulation of gummy or adhesive matter upon the cutters.

I will first proceed to describe what I consider the best means for carrying out my invention, and will afterwards designate the points which I believe to be new.

The accompanying drawings form a part of this specification.

Figure 1 is a front view.

Figure 2 is a side view.

Figure 3 is a plan view; and

Figure 4 is a view of a portion, as seen from within.

Similar letters of reference indicate like parts in all the figures. Tints are employed merely to aid in distinguishing parts, and do not necessarily imply differences of material. The material of the metallic parts may be iron and steel. The framing or case may be made of hard wood.

A is a fixed framework, which may be bolted down, or otherwise firmly secured upon the floor. B B are the two sides of a stationary box or casing, mounted upon the framework A, and between which the tobacco is introduced. These sides are not exactly parallel; they are a little wider apart at the feed-rollers. B' is a mouth-piece or plate, preferably of iron or steel, through which the compressed and compacted tobacco is slowly discharged, and is cut by cutters traversing across, as will be readily understood. This mouth-piece B' is bolted to the sides B B, and connects them firmly at the front end. C is an arbor or shaft, driven by a belt not represented, running on the pulley C', and impelled by a steam-engine or other suitable power. D¹ D² are stout arms, very rigidly secured on the axis C, and carrying knives d d, which, as the shaft C revolves, are carried in close proximity across the face of the mouth-piece B'. These knives sever the tobacco as it is slowly forced out through the said mouth-piece. E is a broad emery-wheel or emery-roller. It is mounted in bearings supported on the framework as represented, and is rotated rapidly by a round belt, not represented, which runs on the pulley E', on the prolonged end of the shaft. Each knife touches this rapidly-revolving emery-wheel at each revolution, and the action of the grinding-surface keeps the cutters sharp. G is a casing, preferably of metal, which encloses the emery-wheel E on all sides, except a little space on the front to allow the cutters to be successively presented. This casing G stands at a little distance from the rapidly-revolving surface of the emery-wheel, and is filled with steam through the pipe g, steam being supplied from a boiler, not represented. The steam keeps the emery-wheel hot and damp, and the moisture imparted to the cutters d d by the moisture of the emery-wheel, and by the small quantity of steam which is allowed to escape from the aperture in the front of the casing G, tends very effectually to prevent any accumulation of gummy matter on the cutters.

My machine treats the tobacco in a novel manner previous to its issuing through the mouth-piece B'. On being introduced between the sides B B, it rests on a slowly-traversing endless apron, H, which is carried on drums h¹ h², as indicated in dotted lines in fig. 2. The stock is fed forward by this means, and is seized by two stout and accurately-turned rollers, I¹ I², shown in strong lines in figs. 1 and 3, and in dotted lines in fig. 2. These rollers are perfectly cylindrical, and fill very nearly the entire space at that point between the sides B B, the sides being peculiarly adapted at this point, as will be described further on. Stout worm-wheels J¹ J² are fixed on the shafts of these feed-rollers, just outside of the casing B B, and their peripheries are simultaneously acted on by the single worm K, mounted in bearings on the outside of the casing B B, and connected so as, like the drums h¹ h², to receive a slow rotatory motion from the driving-shaft C by gearing of an ordinary character, which I do not deem it necessary to represent. It may be sufficient to say that the connection is made by gearing and worm-wheels, the connection extending across under the framework A.

It will be understood that this arrangement imparts a steady but very slow rotatory movement to the feed-

rolls $I^1 I^2$, and that a corresponding forward movement is given to the highly-compressed mass of tobacco which is delivered through the same, and is urged forward to be cut on its exit from the mouth-piece B' . In order to properly confine the tobacco laterally, I provide side-plates $m m$, of polished iron or other suitable material, which are introduced and form a lining, so to speak, to the side-pieces $B B$ along the surface where the tobacco is being compressed by the rollers. One of these pieces detached, with some of the adjacent parts, is represented in fig. 4. A portion of each of these side-plates is shown in fig. 3. Each side-plate extends into the diminishing space or bite between the rolls, and practically confines the width of the casing between which the tobacco is confined to a width less than the cylindrical part of the feed-rolls $I^1 I^2$. Just at the point where the tobacco is most compressed between the feed-rolls, that is to say, just in a line between the axes of the feed-rolls $I^1 I^2$, the side-plates $m m$ terminate. At this point, therefore, the tobacco, after being held laterally to endure the full compressing action of the rolls $I^1 I^2$, is relieved from further lateral pressure. In other words, the highly-compressed and accurately-squared mass of tobacco is relieved from pressure, both laterally and vertically, as it passes the line of centres of the feed-rolls. Thence it is fed forward in a dense mass, enclosed in a suitable casing, M , both laterally and vertically, until it reaches the mouth-piece B' . This mouth-piece, instead of being of uniform size with the casing M , as has been the form of the mouth-pieces of previous tobacco-machines, is contracted, so that the tobacco, instead of meeting with great-resistance from friction during its whole passage through the casing M , and thus holding back the progress of the entire mass, is relieved from pressure, except at the mouth, and is allowed to move freely, but it is tightly compacted and supported on all sides just previous to its being acted on by the cutters.

I have tested this portion of my mechanism very carefully, and have found it to produce an admirable effect. The tobacco is cut very uniformly, and the feeding, as thus arranged, is very efficient and uniform.

I can gear my feeding-mechanism to feed as little or as much between each stroke of the cutters as may be required for the several kinds or grades to be produced.

My machine avoids some very serious difficulties incident to tobacco-cutting machines heretofore employed. I may remark that the cutters of the ordinary tobacco-machines require to be removed and ground after operating only about one minute.

Some of the advantages due to certain features of my invention may be separately enumerated, as follows:

First. By reason of the fact that my tobacco is fed forward by the feed-rolls $I^1 I^2$, made of large size, either plain, as represented, or ridged longitudinally, spirally, or otherwise, I am able to compress effectually and without so much bending the material, as would be required with small rolls acting on a small area, and can, by the great surface thus afforded, urge forward the material efficiently, and can deliver the tobacco to the cutters $d d$ in a highly compact form, and with a very uniform feed, without the crushing of the stock due to the joints of chains or the like, and with very simple, cheap, and durable mechanism.

Second. By reason of the fact that my passage through the early part of the casing M is larger than the space between the rolls $I^1 I^2$, I allow the tobacco to move forward without serious resistance from friction, while it is still sufficiently guided and sustained, and by reason of the fact that my throat B' is contracted at the point of cutting, I compress the mass of tobacco, and thereby cause the cut to be uniform, and prevent portions or ends of the leaves from being drawn through by the cutters in large pieces, instead of being finely cut.

Third. By reason of the fact that the sides $B B$ diverge toward the feed-rolls, I secure an easy and gentle contact of the sides against the material, while I allow the material to be packed between the sides by the hands or otherwise, with all the force which is available, and, as the tobacco moves forward, insure an easy and gentle contact of the sides, and only a slight resistance, due to friction against the same, while it is still efficiently guided and supported.

Fourth. By reason of the fact that the plates $m m$ are fitted closely to the contour of the rolls, and fill the space between the same at each end, as represented, I am able to produce a smoother and more firmly-compressed edge to the mass to be forced forward through the casing M , with less fine or thin material projecting beyond the corners, than would otherwise be possible with equally cheap and simple means.

Fifth. By reason of the fact that my cutters $d d$ are acted on at each revolution by the emery-wheel E , I am able to maintain an extremely sharp cutting-edge on each cutter for a much longer period than is usual in tobacco-machinery.

Sixth. By reason of the fact that the steam received through the pipe g into the casing G is applied to moisten the surfaces of the cutters $d d$ at each revolution, I am able to insure just a sufficient degree of moisture on the cutters to prevent the adhesion of gummy or adhesive matter to the latter, without the deleterious effects which would arise from the presence of any considerable quantities of water on the surfaces.

Having now fully described my invention, what I claim as new, and desire to secure by Letters Patent is as follows:

1. I claim the feed-rolls $I^1 I^2$, conducting-case M , and cutters $d d$, combined as and for the purpose herein set forth.

2. I claim the contracted mouth-piece B' , adjacent to the cutter d , arranged as represented relatively to the passage M and rolls $I^1 I^2$, as and for the purposes herein set forth.

3. I claim the diverging sides $B B$ of the feed-box, as and for the purpose herein specified.

4. I claim the plates m , constructed and arranged relatively to the feed-box $B B$ and feeding-devices $I^1 I^2$, as and for the purposes herein set forth.

5. I claim the grinding-surface E , arranged and operated relatively to the cutters substantially as represented, so as to sharpen the knives or cutters $d d$ while they are in operation, substantially as and for the purpose herein set forth.

6. I claim the application of steam to the cutters *d d* or their equivalents previous to each cut, by conducting the steam from a boiler or the like into the casing through or past which the cutters revolve, substantially as and for the purpose herein set forth.

L. W. SPENCER.
